UNITED STATES PATENT OFFICE.

JONATHAN AMBROSE MERRILL AND ALBION KEITH, OF PORTLAND, MAINE.

DESIGN FOR A SPOON, &c.

SPECIFICATION forming part of Design No. 21,017, dated August 25, 1891.

Application filed March 5, 1891. Serial No. 383,940. Term of patent 7 years.

To all whom it may concern:

Be it known that we, JONATHAN AMBROSE MERRILL and ALBION KEITH, citizens of the United States, residing at Portland, in the county of Cumberland and State of Maine, have invented and produced a new and useful Design for a Spoon; and we do hereby declare that the following is a full, clear, and exact description of the same, reference being had to the accompanying drawing, forming a part thereof.

The drawing shows the handle in top plan.

The leading feature of our design consists in a bust of the poet Henry W. Longfellow stamped, engraved, or molded, or etched upon the handle. The bust is applied to the upper part or end of the handle and is in profile, as shown in the drawing.

A is the handle, and a the stem of the handle. The upper part of the handle b is of an oval or circular form. Below the oval b the handle contracts in width till it meets the stem a, the sides of which consist of waving lines broken at intervals, as shown in the drawing. The oval portion b of the handle is surrounded, except at the lower part, with a

wreath or garland of leaves c, which inclose a portrait bust d of the poet Longfellow in profile. Beneath the bust are waving lines or scroll-work e, between which and the stem a are the letters "H W L" in monogram. At either end of the stem is a leaf f, the stem of the leaf being upward. Between these leaves upon the stem a is the word "Portland," the letters being one above the other and reading downward toward the bowl, tines, or blade of the utensil with which the handle is used. The design is intended for the handles of spoons, forks, knives, &c., of gold, silver, platinum, composition, or other similar material.

What we claim is—

The design for a handle for a spoon, knife, or fork, as herein shown and described.

In testimony that we claim the foregoing as our invention we have hereunto set our hands this 2d day of March, A. D. 1891.

JONATHAN AMBROSE MERRILL.
ALBION KEITH.

In presence of—

GEO. E. BIRD,
WILLARD F. KEITH.
